METHOD OF TREATING TOPICAL SKIN DISORDERS WITH BENZOXATHIOL COMPOSITIONS

Alex Berg and Herbert Fiedler, Biberach (Riss), Germany, assignors to Dr. Karl Thomae G.m.b.H., Biberach (Riss), Germany, a corporation of Germany

No Drawing. Application June 29, 1956

Serial No. 594,678

Claims priority, application Germany July 2, 1955

3 Claims. (Cl. 167—58)

This invention relates to a new and valuable composition for the care of hair and skin and more particularly to a composition containing benzoxathiol compounds which composition has proved of great value for the care of hair and skin and especially for combating scaly skin diseases such as pityriasis capitis, seborrhea sicca or oleosa, and the like.

It is known that formation of scales upon the scalp may be the starting point of progressive alopecia. Scaling of the skin is a natural process. Such scales are removed from the hairless skin by regularly washing the body. Growth of hair on the scalp, however, inhibits more or less natural desquamation of the dead skin scales on the scalp. Insufficient care of hair and scalp causes formation of a layer of such dead scales covering the scalp. Said scales may agglutinate with the secretions of the sebaceous glands and the sweat glands thereby considerably impairing normal functioning of the skin. The fungus *Pityrosporon ovale* is almost always found on the scalp of persons afflicted by scaly skin diseases because such scalp provides excellent living conditions therefor. As a result thereof the skin metabolism is ultimately completely disturbed producing conditions seriously affecting the cosmetic properties of the hair and the scalp and, for instance, causing more or less pronounced falling out of hair.

It is known to combat the above described symptoms of scaly skin diseases by treating the scalp with compositions containing sulfur, tar, or selenium, or, respectively, with hyperemia producing compounds, extracts of certain herbs, astringent or bactericidal agents. Such agents, if continually used, may more or less completely remove the scaly layers on the scalp and may normalize the metabolism of the skin. Thus, they may overcome mild forms of scaly skin diseases. Severe cases of seborrhea, however, remain unaffected or show improvement for a short period of time only when treated with these known sulfur, tar or selenium compounds.

It is one object of the present invention to provide a composition for the care of hair and skin which composition causes desquamation of the dead scales that lie on the scalp surface and are intermingled with the secretions of the sebaceous and sweat glands, in a surprisingly short period of time, which composition is highly effective in the treatment even of severe cases of seborrhea, is well compatible to the human skin and scalp and does not cause irritation thereof, has a strong hyperemia producing effect even in relatively low concentrations, and, therefore, has a strong invigorating effect on the metabolism of the skin.

Another object of the present invention is to provide a simple and effective method of treating seborrhea and the like scaly diseases of the skin and of strengthening the adjacent hair on pilous skin areas of the human body.

Other objects of the present invention and advantageous features thereof will become apparent as this description proceeds.

2

In principle, the new compositions for the care of hair and skin according to the present invention contain, as effective ingredient, a benzoxathiol compound of the following formula

5

10

In said formula R₁ indicates hydrogen, an alkyl radical with 1 to 5 carbon atoms, an aralkyl radical such as the benzyl radical, an aryl radical, such as the phenyl radical, an acyl radical such as the acyl radical of a lower alkanic acid, benzoic acid, nicotinic acid, the hydroxyl group, a lower alkoxy group with an alkyl radical with 1 to 5 carbon atoms, an aralkoxy group such as the benzyl-oxy group, an aryloxy group, such as the phenyloxy group, an acyloxy group, such as a lower alkanoyl group, the benzyloxy group, the nicotinoyloxy group, the sulfhydryl group (—SH), or the acylated sulfhydryl group (—S-acyl group); R₂ indicates hydrogen, the hydroxyl group, halogen, the carboxyl group (—COOH), the carbalcoxy group (—COO-alkyl), such as the carbo(lower) alkoxy group, an alkoxy group such as a lower alkoxy group, an alkyl radical with 1 to 6 carbon atoms, the acyl group, the nitro group, or the amino group; while X is a bivalent hetero atom or a bivalent group of hetero atoms, such as oxygen, sulfur, or the imino group. When R₂, in the above formula, is a nitro group or an amino group, R₁ is preferably the hydroxyl group, the acyloxy group, or the benzyloxy group while X represents the same substituents as indicated above.

Compositions containing such compounds possess remarkable bactericidal and fungistatic activity. They are also well tolerated by the human skin and scalp. They produce strong hyperemia even in low concentrations and, therefore, intensely invigorate the metabolism of the skin. Due thereto they are capable of completely eliminating the layers of scales on the skin surface which are agglutinated with skin secretion. A further characteristic property of such compounds is their ability to strengthen and harden the keratin of skin and hair. They are neither toxic nor irritating to swing nor do they sensitize the skin in the concentrations in which they are applied thereto.

Compositions according to the present invention can be used in various forms. Aqueous, aqueous-alcoholic, or alcoholic solutions of such compounds may be prepared. The compounds may also be incorporated into suitable water-in-oil emulsions or oil-in-water emulsions. They may furthermore be added to non-alkaline washing and wetting preparations adapted for the care of hair and skin. Due to their hyperemia producing, bactericidal, and keratoplastic properties, they may be incorporated into all preparations to be used generally for the care of the skin.

The following examples are given to illustrate the many possibilities of application of benzoxathiol compounds according to the present invention which, of course, is not limited to said examples.

Example 1

	Alcoholic solution:	Percent
40	4-hydroxy-2-oxo-benzoxathiol	1 to 5
50	Water	30
70	Perfume	Q.s.
	Ethanol, sufficient to make 100%	

3

Example 2

Water-in-oil emulsion:	Percent
5-chloro-4-hydroxy-2-oxo-benzoxathiol	1 to 5
Wool fat	15
White beeswax	3
White petrolatum	30
Perfume	Q.s.
Water, sufficient to make 100%.	

Example 3

Hair washing preparation:	Percent
4-nicotinoyloxy-2-oxo benzoxathiol	1 to 5
Neutral alkyl aryl sulfonate	60
Magnesium stearate	2
Oleyl alcohol	1
Water, sufficient to make 100%.	15

Example 4

Aqueous solution:	Percent
4-hydroxy-2-imino benzoxathiol hydrochloride	1 to 5
Glycerol	5
Boric acid	1.5
Rose water, sufficient to make 100%.	

Example 5

Oil-in-water emulsion:	Percent
4-hydroxy benzoxathiol-2-thione	1 to 5
Cetyl alcohol	8
Octadecyl alcohol	8
Wool fat	5
Glycerol	8
p-Hydroxy benzoic acid methyl ester	0.2
Water, ad 100%.	

Example 6

Powder:	Percent
5-hydroxy-2-oxo benzoxathiol	1 to 5
Titanium dioxide	5
Zinc oxide	2
Myristic acid isopropyl ester	1
Talc, ad 100%.	

Example 7

Mixture to be shaken before application:	Percent
4-acetoxy-2-oxo-benzoxathiol	1 to 5
Talc	10
Zinc oxide	10
Sorbitol	15
Water, ad 100%.	

Example 8

Aqueous alcoholic solution:	Percent
5-methyl-2-imino-benzoxathiol	1 to 5
Water	25
Perfume	Q.s.
Ethanol, ad 100%.	

Example 9

Water-in-oil emulsion:	Percent
5-methyl-2-oxo benzoxathiol	1 to 5
Wool fat	10
White beeswax	3
Cetyl alcohol	1
White petrolatum	32
Perfume	Q.s.
Water, ad 100%.	

Example 10

Powder:	Percent
5-chloro-2-oxo benzoxathiol	1 to 5
Titanium dioxide	3
Zinc oxide	5
Colloidal silica	0.5
Sodium lactate	0.2
Wool fat	0.5
Perfume	Q.s.
Talc, sufficient to make 100%.	

4

Example 11

Mixture to be shaken before application:	Percent
2-oxo benzoxathiol	1 to 5
Zinc oxide	3
Titanium dioxide	5
Talc	15
Glycerol	12
Water, ad 100%.	

Example 12

Shampoo:	Percent
5-methyl benzoxathiol-2-thione	1 to 5
Neutral alkyl aryl sulfonate	60
Cetyl alcohol	2
Wool fat	1
Water, ad 100%.	

Since the preparation of such compositions, solutions, emulsions, mixtures, powders, shampoos, and the like are well known and familiar to those skilled in the art, it is only necessary for an understanding of the present invention to describe the composition of such preparations.

In place of the benzoxathiol compounds used as active ingredients in the above given examples, there can be employed other benzoxathiol compounds such as the following compounds while otherwise the composition is substantially the same:

4,6-dihydroxy-2-imino benzoxathiol
6-methyl-4-hydroxy-2-imino benzoxathiol
5-chloro-4-hydroxy-2-imino-benzoxathiol
5-bromo-4-hydroxy-2-oxo benzoxathiol
5-chloro-4-hydroxy-2-oxo benzoxathiol
5-acetoxy-2-oxo-benzoxathiol
35 4-hydroxy-2-oxo benzoxathiol-7-carboxylic acid
4-methoxy-2-oxo benzoxathiol
4-hydroxy-2-oxo benzoxathiol-5,7-dicarboxylic acid
5-nitro-4-hydroxy-2-oxo benzoxathiol
5,7-dinitro-4-hydroxy-2-oxo benzoxathiol
5-amino-4-hydroxy-2-oxo benzoxathiol
4-methyl-5-hydroxy-2-imino benzoxathiol

and others. Such compounds are prepared, for instance, according to methods described by Pantlitschko in "Monatshefte fuer Chemie," vol. 81, page 293 (1950); by Kaufmann in "Arch. Pharm." vol. 267, page 192 (1929).

Especially suitable compounds useful for preparing compositions for the care of hair and skin are benzoxathiol-2-thione compounds of the following formula

wherein R₁ indicates a hydroxyl group, an alkyl radical with 1 to 5 carbon atoms, an aralkyl radical such as the benzyl radical, an aryl radical, such as the phenyl radical, an acyl radical such as the acyl radical of a lower alkanic acid, benzoic acid, nicotinic acid, a lower alkoxy group with an alkyl radical with 1 to 5 carbon atoms, an aralkoxy group such as the benzyloxy group, an aryloxy group such as the phenoxy group, an acyloxy group such as a lower alkanoyloxy group, the benzyloxy group, the nicotinoyloxy group, the sulphydryl group (—SH), or the acylated sulphydryl group (—S-acyl group); and R₂ indicates the hydroxyl group, halogen, the carboxyl group (—COOH), the carbalkoxy group (—COO alkyl) such as the carbo-(lower) alkoxy group, an alkoxy group such as a lower alkoxy group, an acyl group, the nitro group, or the amino group; one of the R₁ and R₂ substituents may also be hydrogen.

Such benzoxathiol-2-thione compounds possess considerable bactericidal and fungicidal or fungistatic proper-

ties and, thus, are excellent disinfectants. They have proven to be highly effective therapeutic agents for the treatment of seborrhea.

In addition to and in place of the 4-hydroxy benzoxathiol-2-thione of Example 5 and the 5-methyl benzoxathiol-2-thione of Example 12, there may be used for the purpose of the present invention other benzoxathiol-2-thione compounds, such as the following compounds while otherwise the composition of the preparations according to the present invention is substantially the same:

4-methoxy benzoxathiol-2-thione
5-chlor-4-hydroxy-benzoxathiol-2-thione
6-methyl-4-hydroxy-benzoxathiol-2-thione
4-acetoxy-benzoxathiol-2-thione
5-nitro-4-hydroxy-benzoxathiol-2-thione
5-amino-4-hydroxy-benzoxathiol-2-thione

Such benzoxathiol-2-thione compounds are obtained in a simple manner, for instance, by reacting the corresponding 2-imino benzoxathiol compounds or their salts in neutral or acid medium with hydrogen sulfide or compounds capable of splitting off hydrogen sulfide in an organic solvent which is unaffected by the reagents such as glacial acetic acid, propionic acid, ether, dioxane, alcohols, benzene, toluene, or xylene and others. This reaction proceeds according to the following equation:

4-hydroxy benzoxathiol-2-thione is, for instance, prepared in the following manner:

50 gm. of 4-hydroxy-2-imino benzoxathiol hydrochloride are suspended in 250 cc. of glacial acetic acid. The suspension is heated under reflux and hydrogen sulfide is passed through the suspension for 3 hours. Most of the solvent is removed by distillation in a vacuum. The concentrated residue is precipitated by means of ice water. Crude 4-hydroxy benzoxathiol-2-thione is obtained with a yield of 70% of the theoretical yield. Yellow crystals of the melting point 124-127° C. are obtained on recrystallization from toluene.

5-methyl benzoxathiol-2-thione is obtained in an analogous manner. Recrystallization from ethanol yields yellowish crystals of the melting point 106-108° C.

Another method of producing such benzoxathiol-2-thione compounds comprises the reaction of substituted o-mercapto phenols with thiophosgene in the presence of an acid binding agent such as alkali metal hydroxides or carbonates or tertiary organic amines, such as pyridine or dimethyl aniline, in an inert medium, such as water, aqueous acetone or dioxane.

4-methoxy benzoxathiol-2-thione is obtained, for instance, by dissolving 7.7 gm. of 1-methoxy-2-mercapto-3-hydroxy benzene in 70 cc. of an aqueous solution of 4 gm. of sodium hydroxide. 2 cc. of thiophosgene are added to said solution while cooling. The precipitated red crystals are purified by recrystallization from ethanol and form flesh-colored needles of the melting point 104-106° C.

Another very valuable group of compounds are halogenated benzoxathiol compounds of the following formula:

wherein R₁ indicates hydrogen, an alkyl radical with 1 to 5 carbon atoms, an aralkyl radical such as the benzyl radical, an aryl radical, such as the phenyl radical, an acyl radical such as the acyl radical of a lower alkanic acid, benzoic acid, nicotinic acid, the hydroxyl group, a

lower alkoxy group with an alkyl radical with 1 to 5 carbon atoms, an aralkoxy group, such as the benzyloxy group, an aryloxy group such as the phenoxy group, an acyloxy group such as a lower alkanoyloxy group, the benzyloxy group, the nicotinoyloxy group, the sulphydryl group (-SH), or the acylated sulphydryl group (-S-acyl group); and R₂ indicates hydrogen, the hydroxyl group, halogen, the carboxyl group (-COOH), the carbalkoxy group (-COO alkyl), such as the carbo-(lower) alkoxy group, an alkoxy group such as a lower alkoxy group, an alkyl radical with 1 to 6 carbon atoms, the acyl group, the nitro group, or the amino group; R₃ indicates hydrogen or halogen; and R₄ indicates halogen; while X is a bivalent hetero atom or a bivalent group of hetero atoms, such as oxygen, sulfur, or the imino group. The term "halogen" as used herein and in the claims annexed hereto indicates chlorine, bromine, and iodine.

Compounds of this composition are obtained by directly halogenating compounds of the formula

wherein R₁, R₂ and X represent the above indicated substituents with the exception of halogen, by means of halogenating agents according to methods used for introducing 1 to 3 halogen atoms into the benzene nucleus. Such halogenating agents, are, for instance, elementary halogen, thionyl halogenide, sulfonyl halogenide, phosphorus halogenides, halogen in statu nascendi such as hydrogen halide in the presence of an oxidizing agent such as manganese dioxide or potassium chlorate. Such direct halogenation of the benzene nucleus is carried out in solution or suspension in a suitable reaction medium, preferably in acid aqueous solution or in organic solvents such as ether, glacial acetic acid, dioxane, benzene.

30 5,7-dichloro-4-hydroxy-2-oxo benzoxathiol is, for instance, obtained by dissolving 100 gm. of 4-hydroxy-2-oxo benzoxathiol in 1000 cc. of ether and 100 cc. of glacial acetic acid. Chlorine is introduced until the solution is saturated therewith. The mixture is allowed to stand at room temperature for 3 to 5 hours. The solvent is distilled off. The crystallizing residue, obtained in a yield of 95% of the theoretical yield, is recrystallized from 30% ethanol and yields white crystals of the melting point 180-182° C.

35 5-chloro-4-hydroxy-2-oxo benzoxathiol is, for instance, obtained by dissolving 84 gm. of 4-hydroxy-2-oxo benzoxathiol in 500 cc. of glacial acetic acid and 200 cc. of concentrated hydrochloric acid. An aqueous solution of 20.4 gm. of potassium chlorate is slowly added thereto while cooling. After the reaction is completed, the reaction mixture is poured into water. Reddish crystals precipitate which are recrystallized from toluene with the addition of animal charcoal. White crystals of the melting point 156-158° C. are obtained. Yield: 80-85% of the theoretical yield.

40 Other halogenated benzoxathiol compounds are obtained in an analogous manner, such as

45 5,7-dibromo-4-hydroxy-2-oxo benzoxathiol
5-bromo-4-hydroxy-2-oxo benzoxathiol-7-carboxylic acid
5-bromo-4-hydroxy-2-oxo benzoxathiol
7-chloro-5-bromo-4-hydroxy-2-oxo benzoxathiol
5,7-dibromo-4,6-dihydroxy-2-oxo benzoxathiol

and others.

50 It has been found that compositions for the care of hair and skin according to the present invention preferably contain at least about 0.01% of the benzoxathiol compounds. A lower content of such compounds is not sufficiently effective and does not cause satisfactory desquamation. An amount of about 15% should not be ex-

ceeded since it might have an irritating effect on the skin, especially if such skin has become infected by bacteria and fungi and inflamed by their action. The concentration of benzoxathiol compounds of between about 0.01% and about 15% especially between about 1% and about 5% is a characteristic feature of the present invention and produces optimum effects.

The new compositions are applied to the hair and scalp, for instance, by rubbing a solution or emulsion thereon or by applying thereto a wet dressing. The hair and 10 skin may also be dusted with powder compositions.

Care of the scalp is essential. If a shampoo is applied, it should be followed by a rinse of dilute white vinegar and, thereafter, with water. Scalp and hair should be brushed carefully to remove dirt and scale.

Another method of application consists in massaging the scalp with an ointment or a paste containing the active benzoxathiol compound.

Application of an alcoholic-aqueous solution of 4-hydroxy-2-oxo benzoxathiol (Example 1) to the hair and scalp resulted in complete elimination of scaly skin afflictions. The application having only benzoxathiol compounds is applied each night, after washing. The skin may also be covered with a night cream containing the active ingredient.

Other methods of application as they are used by the medical profession may, of course, also be employed.

While we have given several examples of the practice of our invention, it will be understood that many changes and variations in the benzoxathiol compound used, in the composition of the preparations for the care of hair and skin, in the solvents, emulsifying, wetting, and the like agents employed, in the manner in which such preparations are applied to hair and skin, and the like may be made by those skilled in the art in accordance with the principles set forth herein and within the following claims.

We claim:

1. The method of therapeutically alleviating topical scaly skin disorders and strengthening the adjacent hair on 40

5 pilous skin areas of the human body, which comprises topically applying to the affected skin areas and to the adjacent hair a benzoxathiol compound having the structural formula

wherein R₁ is selected from the group consisting of hydrogen, alkyl with 1 to 5 carbon atoms, aralkyl, aryl, acyl, hydroxyl, alkoxy with 1 to 5 carbon atoms, aralkoxy, aryloxy, acyloxy, sulphydryl, and acylated sulphydryl; R₂ is selected from the group consisting of hydrogen, hydroxyl, halogen, carboxyl, carbalkoxy, alkoxy, alkyl with 1 to 6 carbon atoms, acyl, nitro and amino; R₃ and R₄ are selected from the group consisting of hydrogen and halogen; and X is selected from the group consisting of oxygen, sulfur and imino, in dosage form in a concentration ranging from 0.01 to 15% in an inert pharmaceutical carrier.

25 2. The method of therapeutically alleviating topical scaly skin disorders and strengthening the adjacent hair on pilous skin areas of the human body, which comprises topically applying to the affected skin areas and to the adjacent hair 4-hydroxy-2-oxo-benzoxathiol in dosage form in a concentration of from 0.01 to 15% in an inert pharmaceutical carrier.

30 3. The method according to claim 2, wherein the inert pharmaceutical carrier is a 60% aqueous isopropyl alcohol solution.
